UNITED STATES PATENT OFFICE.

RUDOLF THIELE, OF HOXTER-ON-THE-WESER, GERMANY.

CONTINUOUS FURNACE FOR BURNING CEMENT AND THE LIKE.

Application filed August 12, 1916. Serial No. 114,514.

(GRANTED UNDER THE PROVISIONS OF THE ACT OF MARCH 3, 1921, 41 STAT. L., 1313.)

To all whom it may concern:

Be it known that I, RUDOLF THIELE, a subject of the King of Prussia, and resident of Hoxter-on-the-Weser, in the Kingdom of Prussia, Empire of Germany, head manager, have invented certain new and useful Improvements in Continuous Furnaces for Burning Cement and the like (for which applications have been filed in Germany, May 5, 1915, Patent No. 293,284; Germany, April 7, 1916, Patent No. 297,753; Austria, April 25, 1916, Patent No. 86,191; Switzerland, May 10, 1916, Patent No. 73,899; Denmark, May 12, 1916, Patent No. 22,066; Norway, May 15, 1916, Patent No. 28,155; Sweden, May 15, 1916, Patent No. 41,972; Hungary, May 17, 1916, Patent No. 70,350; France, May 23, 1916, Patent No. 512,991; England, May 30, 1916, Patent No. 101,937; 10 Belgium, June 13, 1916, Patent No. 271,241; Italy, June 24, 1916, Patent No. 507/170-154,673; Turkey, July 5, 1916, Patent No. 2,632; Spain, October 18, 1916, Patent No. 63,133; Luxemburg, October 24, 1919, Patent 20 No. 11,533; Poland, November 11, 1919, no patent issued as yet; Roumania, June 6/19, 1916, no patent issued as yet; Czechoslovakia, January 25, 1922, Patent No. 8,177; 25 Czechoslovakia, March 16, 1922, no patent 30 issued as yet), of which the following is a specification.

My present invention relates to the class of furnaces in which more or less intensely baking materials for the manufacture of cement and the like are burnt in a continuous operation, but more particularly to a crushing- and delivering-device thereof.

The object of my invention is to replace the stationary grate forming the bottom of such furnaces by a reciprocating shearing-grate, by the aid of which the burnt materials may be not only comminuted but also continuously delivered. Since the weight to be supported by the grate of such furnaces is exceedingly great, the force to reciprocate it must of necessity be great too and for this reason would, if applied at one side only, endanger the furnace. To successfully avoid this I build the grate up of two sections or halves, place these side by side and apply to each of them one half of the operative force in such a manner, that the two sections, forming practically a single horizontal grate, are simultaneously operated in opposite directions in the plane of

said grate. In doing so the detrimental actions of the operative forces upon the structure of the furnace are wholly avoided.

To facilitate the shearing-action of the grate, the grate-bars arranged crosswise to the direction of the grate-motion are connected with each other by grate-bars forming an acute angle with said direction of grate-motion, so that the combined grate-bars will form a kind of lattice-work. Other peculiarities of my lattice-shearing-grate designed to increase the shearing-action thereof will be duly pointed out in the specification and claimed in the appended claims.

Since the operative forces are necessarily great, the driving-rods coupling the driving-mechanism with said grate-sections must be carefully protected against flexure and binding. To attain this I hinge to each grate-section a stout driving-rod and guide the external ends of these rods by cross-heads, so that they are subjected to tension and pressure only. The cross-heads are connected by connecting-rods with a double-cranked driving-mechanism having its cranks set at 180° to each other. Besides this the above-named arrangement offers the advantage that in cases where under-blast is employed the delivery-hopper containing the shearing-grate can be easily kept air-tight. To accomplish this I close the apertures through which said driving-rods enter said delivery-hopper by means of two-parted stuffing-boxes the packing of which is kept in contact with the driving-rods by the agency of 80 spring-pressed stuffing-box-sections.

In the accompanying drawings:—

Figure 1 is a vertical sectional view of a furnace built in accordance with my present invention,

Figure 2 is horizontal sectional view taken on line A—B of Figure 1, whereas

Figures 3, 4, 5, 6, 7, 8 are detail views of construction on a larger scale.

The burning-chamber 1 of the furnace F is capped by the hood 2 and is closed at its lower end by a horizontal shearing-grate G arranged above the delivery-hopper 3. The grate G consists of the two grate-sections 4 and 5. By arranging in each grate-section the grate-bars 6 at right angles, and the grate-bars 7 at an acute angle to the direction of the grate-motion, rhombic grate-openings 8 are obtained. Each of the lattice-shearing-frames L thus produced is mount-

60 65 70 75 80 85 90 95 100 105 110

90

ed on a heavy base 9 provided with runners 10 which are supported by rollers 11 to reduce friction. At each end of the runners 10 a ribbed shearing-plate 12 is arranged and provided with a plurality of holes 12^a of considerably less area than the grate-openings 8. Besides this each shearing-plate 12 is armed with a plurality of diamond-shaped teeth or projections 13 to increase the shearing and crushing capacity of said plates. In a similar manner and for the same reason the grate-bars 6 and 7 are armed with teeth 14. Between the runners 10 of each grate-section a cross-piece 15 is secured to which the inner end of a heavy driving-rod 16 is suitably hinged. The outer end of each driving-rod passes outwards through an opening 17 of the furnace-wall and is provided with a cross-head 18 guided by the guide-bars 19 and 20. The cross-heads of both driving-rods are connected with the cranks 21 and 22 of the driving-shaft 23 by means of connecting-rods 24. The cranks 21 and 22 are set at 180° to each other to compel the grate-sections 4 and 5 to reciprocate simultaneously in opposite directions. The worm-wheel 25 of the shaft 23 meshes with the worm 26 of the shaft 27 which by means of the worm-wheel 28 and the worm 29 receives its motion from the shaft 30. The shafts 23 and 27 are suitably journaled on the rigidly braced frame-work 31. The shaft 30, supported on the floor 32, carries a pulley 33 which is connected by a belt 34, chain or the like with a pulley 35 of the shaft 36 journaled in hangers 37 arranged beneath said floor. The shaft 36 receives its motion from an electric motor M which transmits its rotary motion to the pulley 38 of shaft 36 by the aid of a belt 39.

To prevent the blast-air from escaping from the delivery-hopper 3 through the wall-openings 17 a two-part stuffing-box 40 is provided for each driving-rod 16. Each of these stuffing-boxes consists of two flanged sections which are slidingly attached to a wall-plate 41 and subjected to the action of springs 42 arranged between the stuffing-box-sections 43 and the wall-plate-projections 44 upon guide-pins 44^a of the latter. The cups 43^a are in this instance angular in shape to agree with the rectangular cross-section of the driving-rods 16. The springs 42 are arranged diagonally to said driving-rods to simultaneously press both wings of the packing 45 of each stuffing-box-division against two adjacent sides of said driving-rods.

60 The operation of said furnace is as follows:—

The suitable mixture of fuel and raw material for the formation of cement-clinkers or of a clinker-stock is introduced into the burning-chamber 1 through the openings 46

of the hood 2 and the blast-air is introduced by any suitable known means (not shown) into the delivery-hopper 3. After a clinker-stock has been formed both grate-sections are set in motion which, according to the 70 ratio of power-transmission shown, will be comparatively slow. The toothed bars and plates of both grate-sections will now attack from opposite sides the clinker-stock produced by the baking and sintering action of 75 the fuel upon the raw material. The clinker-stock will during the ensuing crushing- and shearing-process be held in equilibrium and therefore be prevented from endangering the furnace-structure. The shearing and 80 crushing action of the grate-sections exerted hereby upon the lower end of the clinker-stock will gradually comminute the latter and the fragments resulting therefrom will, if sufficiently reduced, drop through the 85 openings 8 and 12^a into the delivery-hopper 3. If still too large to pass through said openings they will be retained by the grate-sections until reduced to the required size. It is evident that coarse and exceptionally 90 hard burnt clinker-fragments would be apt to cause the partial or entire destruction of the driving-gear if they should find an opportunity to form a rigid obstacle between the one or the other grate-section and the 95 furnace-wall before the corresponding grate-section could finish its stroke. Opportunities of this kind may, of course, present themselves as often as a clinker-fragment of the kind pointed out above partially enters 100 into a grate-opening 8 and partially projects above the surface of the grate. Such possibilities can, however, be fully excluded by giving each of the shearing-plates 12 a 105 width which must at least equal but may be greater than the stroke of the grate-sections, i. e. the distance to which said sections move back and forth in the pockets formed by the I-beams 47 at the upper part of the delivery-hopper 3. To successfully prevent coarse 110 clinker-fragments from finding a sufficiently sure footing on said plates to enable them to act as dangerous obstacles, the holes 12^a of the plates 12 are, as already stated before, of considerably less area than the openings 8. By this arrangement the driving-gear is fully protected against destruction from this source.

The fragments of the clinker-stock sufficiently reduced by the crushing and shearing actions of the grate-sections to pass through the openings 8 or 12^a into the delivery-hopper 3 are collected in the latter and periodically removed therefrom. This is effected by means of an inclined outtake-channel 48, wherein the oscillating sluice-gates 49 and 50 are arranged one behind another. The shafts 51 of these gates are each provided with a pulley 52, to which a belt 53, chain or the like is attached. Each belt 130

carries at the one end a weight 54 and at the other a toothed guide-bar 55 which is arranged in a bracket 56 in such a manner that during each revolution of the shaft 57 each sluice-gate can be raised by means of a crank 58 of said shaft and be returned again to its initial position by its own weight 54. The rotation of the shaft 57 is caused by the shaft 27, the intermediate shaft 59 and the belts 60 and 61. The speed of the shaft 59 remains constant, whereas the speed of the shaft 57 may be varied by shifting the belt 61 on the stepped cones 62 and 63. The cranks 58 are set at 180° to each other to permit of the opening and closing of the sluice-gate 49 while the sluice-gate 50 remains closed, and vice versa. In operation the clinker-fragments sliding down the channel 48 will, when the gate 49 is opened and the gate 50 shut, advance into the space lying between both gates until the gate 49 is closed. The clinker-fragments thus entrapped will, however, leave this space and the lower end of said channel when in due time the gate 50 will be opened. The closing of this gate will take place before the gate 49 can be opened anew. In this manner the pressure of the blast-air within the delivery-hopper 3 will be kept practically constant.

I claim:—

1. A continuous furnace of the character described, having a shearing-grate consisting of grate-sections adapted to be reciprocated in their own plane in opposite directions to each other, clinker-crushing teeth on said sections and means for reciprocating said grate-sections.

2. A continuous furnace of the character described, having a shearing-grate consisting of two grate-sections adapted to be simultaneously reciprocated in opposite directions in the plane of said shearing-grate, clinker-crushing teeth on said sections and means for simultaneously reciprocating said grate-sections.

3. A continuous furnace of the character described, comprising a shearing-grate, consisting of two grate-sections having their grate-bars combined to form a lattice-shearing-frame and adapted to be simultaneously reciprocated in opposite directions in the plane of said shearing-grate, clinker-crush-

ing teeth on said sections and means for simultaneously reciprocating said grate-sections.

4. A continuous furnace of the character described, having a shearing-grate consisting of grate sections reciprocatable in opposite directions, said grate-sections comprising each a centrally arranged lattice-shearing-frame and two perforated shearing-plates arranged at the ends of said grate-sections; and means for simultaneously reciprocating said grate-sections.

5. A continuous furnace of the character described, having a shearing-grate composed of two grate sections adapted to be simultaneously reciprocated in the plane of said grate, said grate-sections being each provided with a centrally arranged lattice-shearing-frame formed by teeth-studded grate-bars and provided further with perforated shearing-plates arranged adjacent the ends of said lattice-shearing-frame and furnished with shearing-teeth; and means for simultaneously reciprocating said grate-sections.

6. A continuous furnace of the character described, having a shearing-grate composed of two grate-sections adapted to be simultaneously reciprocated in opposite directions in the plane of said shearing-grate; said grate-sections being each equipped with a centrally arranged lattice-shearing-frame composed of one set of teeth-studded grate-bars arranged at right angles to the direction of the grate-motion and of another set of teeth-studded grate-bars arranged at an acute angle thereto, and equipped also with two shearing-plates equaling in width at least the stroke of said grate-sections and provided with openings of less area than the openings of said lattice-shearing-frame and further provided with diamond-shaped shearing-teeth having their longer diagonal pointing in the direction of grate-motion; and means for simultaneously reciprocating said grate-sections.

Signed by me at Hanover, Germany, at 100 this 7th day of April, 1916.

RUDOLF THIELE.
